(57) **CLAIM**

I claim the ornamental design for a folding retractable wing assembly for toys, as shown and described.

DESCRIPTION

FIG. 1 is a rear perspective view of the design, with the wings folded and retracted;

FIG. 2 is a rear elevation view thereof;

FIG. 3 is a left side elevation view thereof;

FIG. 4 is a right side elevation view thereof;

FIG. 5 is a top elevation view thereof;

FIG. 6 is a bottom elevation view thereof; and

FIG. 7 is a front elevation view thereof.

FIG. 8 is a rear perspective view of the design, with the wings folded and extended;

FIG. 9 is a rear elevation view thereof;

FIG. 10 is a left side elevation view thereof;

FIG. 11 is a right side elevation view thereof;

FIG. 12 is a top elevation view thereof;

FIG. 13 is a bottom elevation view thereof; and

FIG. 14 is a front elevation view thereof.

FIG. 15 is a rear perspective view of the design, with the wings unfolded and extended;

FIG. 16 is a rear elevation view thereof;

FIG. 17 is a left side elevation view thereof;

FIG. 18 is a right side elevation view thereof;

FIG. 19 is a top elevation view thereof;

FIG. 20 is a bottom elevation view thereof; and,

FIG. 21 is a front elevation view thereof.
